UNITED STATES PATENT OFFICE.

WILLIAM B. MOTHERAL, OF NORTH MC GREGOR, IOWA.

DESIGN FOR A VESSEL-HULL.

SPECIFICATION forming part of Design No. 32,547, dated April 17, 1900.

Application filed March 15, 1900. Serial No. 8,849. Term of patent 14 years.

To all whom it may concern:

Be it known that I, WILLIAM B. MOTHERAL, a citizen of the United States, residing at North McGregor, in the county of Clayton and 5 State of Iowa, have invented and produced a new and original Design for a Vessel-Hull; and I do hereby declare the following to be a full, clear, and exact description of the invention, such as will enable others skilled in the 10 art to which it appertains to make and use the same.

This invention relates to a design for a vessel-hull having a bottom of novel outline and shaped so as to secure certain advantages and 15 present a unique appearance.

The essential feature of the design is a vessel-hull of substantially wedge form having its bottom provided with a rounded stern portion, a substantially-flat central portion extending from the inner edge of said stern to the bow, and upwardly and outwardly inclined or beveled edge portions bounding said central flat portion on opposite sides, said beveled edge portions being upwardly inclined to 25 a plane above the flat central portion and thence curved downwardly and rearwardly to the stern-line.

The design will be more particularly described hereinafter in connection with the accompanying drawings, the same reference characters being employed in the description and all the figures of the drawings to designate corresponding and like parts.

In the drawings, Figure 1 is an inverted 35 plan view of a vessel-hull the bottom whereof embodies my design. Fig. 2 is a side eleva-

tion. Fig. 3 is a cross-section on line 3 3 of Fig. 1. Fig. 4 is a similar view on line 4 4 of Fig. 1.

The vessel-hull tapers from stern to bow and 40 is of substantially wedge form, and its stern 1 is approximately flat at its lowest point 2 and thence curves upwardly, as at 3, or is made rounding, as shown clearly in Fig. 3. The central portion 4 of the bottom of the 45 hull tapers longitudinally in conformity therewith and is flat throughout its length and merges at its rear into the inner edge line of the stern. This central portion 4 is bounded on opposite sides by correspondingly-tapering edge portions 5, which are beveled or outwardly and upwardly inclined, as shown in Fig. 4. From the bow 6 the said edge portions 5 project upward rearwardly on a gradual inclination to a plane above the central 55 portion 4, as at 7, and thence curve downwardly and rearwardly, as at 8, and merge into the inner edge of the stern-line. The upward inclination of the rear ends of the beveled edge portions causes the formation of 60 spaces upon either side and above the plane of the flat central portion of the bottom.

Having thus described my invention, what I claim is—

The design for the hull of a vessel, substantially as herein shown and described.

In testimony whereof I affix my signature in presence of two witnesses.

WILLIAM B. MOTHERAL. [I. S.]
